UNITED STATES PATENT OFFICE.

JOZEF GOTERCH, OF LAWRENCE, MASSACHUSETTS.

FILLING-FEELER.

1,290,973.

Specification of Letters Patent. Patented Jan. 14, 1919.

Application filed August 31, 1917. Serial No. 189,106.

To all whom it may concern:

Be it known that I, JOZEF GOTERCH, a citizen of Austria, residing at Lawrence, in the county of Essex and State of Massachusetts, have invented certain new and useful Improvements in Filling-Feelers, of which the following is a specification.

This invention relates to filling feeler devices for looms. Its object is to provide means which will permit as much as possible of the filling on the bobbin in a shuttle to be used before the filling is replenished whereby there will be less filling wasted. It is more particularly adapted for looms in which the filling is automatically replenished, as by the substitution of a full bobbin for an empty one, but it can readily be adapted for use with almost any type of loom.

My device is especially useful on looms in which there is a battery of bobbins which are introduced one after another into a working shuttle. Such looms have a lay beam with a shuttle race and shuttle boxes with filling changing mechanism operative by a movable shifting arm. This shifting arm, whenever it is moved in a predetermined manner through the medium of devices of well known construction operative by feeler mechanism, operates in a well known manner to start the filling changing mechanism which, without stopping the loom, ejects the old bobbin and replaces it by a new one.

My invention relates especially to feelers which operate vertically into or through the bobbin recess in a shuttle. With my device there is no need of cutting a slot through the side of the shuttle to permit the feeler finger to enter as the feeler comes down from the top into the bobbin recess. In my preferred form I use a caliper feeler the legs of which come down on both sides of the bobbin and which can be very accurately adjusted.

My device has few and simple parts and can readily be attached to any of the ordinary looms. It can be adjusted with great accuracy, but has no delicate springs the strength of which is likely to vary. It cannot easily be injured by binding on the shuttle, by the shuttle rebounding, or by any of the various accidents which occur in the operation of looms.

It is so arranged that it cannot bind on the bobbin and will not be injured if the shuttle binder does not work and the shuttle rebounds.

By a very slight change in the shape of my feeler shaft, it can operate various types of shifting arms such as those which are movable horizontally or vertically. I prefer to use it in connection with a vertically movable shifting arm. I also prefer to use in connection with my caliper, an auxiliary feeler which may consist of a single blade at a distance from the main caliper sufficient to reach the middle part of the bobbin.

Such auxiliary blade I find is of advantage in connection with bobbins which are defectively wound as on such bobbins the usual type of feelers which operate in one place only, are not satisfactory.

By sorting out the defectively wound bobbins and using them in a loom provided with my auxiliary feeler, I can save a considerable amount of filling which otherwise would be lost. In this manner, the process of rewinding such bobbins is done away with.

If it seems desirable, in place of calipers, I can use in connection with a bobbin which has a longitudinal slot, a feeler which consists of a single downwardly extending blade in position to enter the slot after the yarn has run out, provided the bobbin is so turned that the slot is vertical instead of horizontal.

When used with a loom having a battery, magazine, or boxes at one side, I prefer to locate my devices at the opposite side.

In the drawings, Figure 1 is an elevation from the front of the loom showing my device in connection with a lay beam, shuttle and other parts with which it is in operative relation. Fig. 2 is a sectional elevation from the left on line 2-2 of Fig. 1. Fig. 3 is a plan view of the feeler shaft and accompanying parts with an auxiliary feeler in place. Fig. 4 is an enlarged view from the right of Fig. 3 on the line 4-4. Fig. 5 is an enlarged view similar to Fig. 4 with the spring plate and spring removed. Fig. 6 is an enlarged detail elevation of the feeler shaft and attachments, including an auxiliary feeler, shown as from the right of line 6-6 of Fig. 1. Fig. 7 is an elevation from the left of Fig. 6, but showing the parts down in position to change the filling. Figs.

8, 9, and 10, show different modifications of the knock-off arm to adapt it for operation with different types of shifting arms. Fig. 11 shows another modification in which an independent knock-off arm is shown as attached to the slide strip through the medium of the hub and feeler shaft. Fig. 12 is a detail view similar to Fig. 7, showing a single feeler member in connection with a vertically slotted bobbin. Fig. 13 is an elevation and Fig. 14 a plan view of my device adapted for a loom in which there is no automatic filling replenishing mechanism, but wherein the shifting arm is arranged merely to operate filling changing mechanism to stop the loom.

In the drawings, M represents the lay, R the shuttle race thereon, A a shuttle box at one end thereof, P a picker, and L a plate attached to and forming part of the lay beam. In this plate L is a vertical slot 19 in which there is, vertically slideable, a slide strip 20. The strips 10 and 11 hold this slide strip in position and it extends upward to a point above the shuttle race, and also down below plate L as shown.

Fixed to this slide strip is a feeler shaft 73 which extends across and over the shuttle race. To this feeler shaft in a position to rock lengthwise of the lay beam is pivoted the vertically operable feeler mechanism to be described.

This slide strip and shaft carrying the feeler devices, are associated with means independent of the shuttle to permit them to drop and to lift them just before the shuttle is picked. Such mechanism is shown as including a connecting rod 22 pivoted to the slide strip at 21 and bent in any suitable fashion to clear the other parts of the loom. Its lower end is substantially vertical, and adjustably attached thereto are the guards 23 and 24.

Fixed to any part of the loom frame such as 37, by means of a frame 36 and a bolt 38, is a standard 35 to the top of which at 33 is pivoted a rocking arm T which extends out around the rod 22 between the guards 23 and 24. This arm T may have a horizontal spring rod 40 extending from it connected to one end of a lifting spring 39, the other end of which is attached at 41 to another part of the frame of the loom.

To arm T is fixed a projection 32 which extends into the line of travel of a cam F carried by any convenient shaft 30 which is preferably the worm shaft which operates the pick mechanism which revolves one turn for each two picks.

The spring 39 will normally keep the arm T raised, and through guard 23, rod 22, and slide 20 will keep the feeler shaft and feeler raised away from the bobbin. At a point which is predetermined so as to be just as the shuttle is entering the shuttle

box, on the side of the loom away from the battery, cam F depresses arm T against spring 39 allowing the feeler arm and feeler to descend by gravity. Just before the shuttle is picked, cam F is so made and timed that projection 32 slips off allowing spring 39 to act in such a manner that the feeler shaft and feeler are suddenly kicked up out of the way of the shuttle. This kick is in the nature of a blow and tends to release the feeler mechanism in case it might otherwise be jammed or bound on the bobbin.

The feeler mechanism includes a hub H pivoted on the feeler shaft, and a caliper feeler which includes one leg 52 integral with hub H, and another leg 53 which is shown as extending up alongside of hub H, and as being pivotal on the feeler shaft and extending downward parallel with leg 52.

The part 53 is attached to the hub H by means of a screw 55. This screw 55 may be headed and have the usual slot for a screw driver. It is shown as unthreaded where it passes through hole 57 in the hub and as threaded the rest of the way to its tip. It also has an annular groove 56 with which a set screw 54 engages whereby it is prevented from moving in or out, but can revolve unless screw 54 is tightened enough to bind.

Leg 53 has a threaded hole 58 through which screw 55 passes and protrudes a considerable distance. By turning screw 55, leg 53 is forced toward or away from leg 52 whereby the distance between them can be accurately adjusted.

Pivoted on feeler shaft 73 is a spring plate 71 which extends downward and is slotted at 81 so as to pass snugly around screw 55 as shown in Fig. 4 and Fig. 6. A returning spring 51 at one end passes through a hole 105 in shaft 73 and at the other end into a hole in spring plate 71, whereby as the parts are held together by screw 55, the spring tends to return them when they are turned against its pressure. This spring is preferably of helical form and long enough to permit of considerable compression to allow the bracket which carries the supplemental feeler 60 to be inserted between the spring plate and leg 53. Its pressure holds these parts together.

To hold the hub in position on its other side, I use a collar 77 which is fixed to shaft 73 by means of a projecting set screw 78. I prefer to so locate this set screw that it will project into the path of the upper back corner 74 of leg 52 and serve as a stop to limit its movement from the pressure of spring 51, whereby it will be held normally in such a position that the caliper feeler formed by legs 52 and 53 will be directly over the bobbin B in the shuttle S.

As shown in Figs. 1, 2, 3, 6, 7, 8, and 9, the feeler shaft after it passes the hub is integral with and forms part of a knock-off arm. 130

This knock-off arm can be bent in various ways, as shown in Figs. 8, 9, and 10, as well as Figs. 1, 2, and 6, so as to be in operative relation with the shifting arm which stops the loom or which changes the filling as, for instance, by ejecting the bobbin from the shuttle and replacing it by a new one.

In Figs. 1, 2, and 6, this shifting arm 84 is shown as located under the knock-off arm 10 and as operable when it is pushed downward by the weight thereof.

In Fig. 8, 100 represents the upturned slanting tip of the knock-off arm, and 101 the shifting arm which, as shown by the dotted lines, will be forced crosswise of the lay beam when the arm descends.

Fig. 9 shows the tip 102 bent at right-angles and angularly so that when the knock-off arm descends, it will force the shifting-arm in a direction lengthwise of the lay beam, as shown by its dotted position, from its full line position 103.

In Fig. 10, I show the tip 104 of the knock-off arm with a double bend so as to reach out and engage the end of the shifting arm 105.

It will be thus seen that by changing the shape of the knock-off arm, which is shown as integral with the feeler shaft, I can readily operate any type of shifting arm, whether it is necessary to move it up and down, to the right or left, or toward and from the lay beam.

As shown in Fig. 11, I may use separate members for the feeler shaft shown as 108, which is cut off beyond collar 77 and the knock-off arm 106, which is shown as attached to hub H by means of a screw 107.

I find it desirable with certain bobbins, especially those which are defectively wound in such a manner that the yarn unwinds from the part near the head where my calipers ordinarily engage the bobbin, before it unwinds from the middle part, to use an auxiliary feeler which will hold up the parts until the yarn at the point where it operates has also unwound.

I find it convenient to equip one of a number of looms with such feeler and to use up all defective bobbins therewith. I arrange my device so that this feeler can be readily attached or removed as I will now describe.

I provide a bracket 59 which is preferably formed of an angular piece of sheet metal 55 with a vertical extension 146 in which from the top there extends downward a slot 145 of such size that it will readily slip upward over shaft 73, and at the bottom a slot 80 of such size that screw 55 will pass through it 60 with a running fit.

The other part of bracket 59 extends out in a direction toward the middle of the bobbin and has near its end a slot 147. The feeler preferably includes a blade 60 of the thickness of the caliper portion of leg 53

which projects downward at the end of a shank 61 to a point where it will engage the yarn along the middle part of the bobbin. A bolt 62 passes through shank 61 and slot 147 and these parts are adjustably held together by means of a nut 148. Shank 61 may be slotted at 149.

With this form of feeler, it can be readily put in position by forcing spring plate 71 to the right against spring 51 and pushing the bracket upward so that slot 145 passes over shaft 73 and then twisting or pushing it to the left so that slot 80 passes over screw 55, and then allowing spring 51 to bring the parts back to their normal position.

With my construction, by adjusting collar 77 and screw 55, my calipers can be made of any desired size and located directly over the center at one end of the bobbin and as the whole mechanism is permitted to drop by the cam and accompanying parts at the time when the shuttle is stationary in the box, if properly adjusted the calipers will stop at the point shown in Fig. 2 until the yarn has been unwound to the predetermined point, after which the calipers, hub, knock-off arm, etc., will drop to the position shown by the dotted lines in Fig. 6, thus operating the filling changing mechanism.

My device avoids the objection to some other caliper feelers that if they strike the wood of the shuttle, in case it rebounds too far, damage is done, as no injury occurs if the wood is struck. Moreover, if the shuttle binder fails to work and the shuttle rebounds after the calipers have engaged the bobbin, no harm is done as the calipers are thrown up out of the way, as shown by the dotted lines in Fig. 7, and are quickly returned to operative position by spring 51.

In my device there are no springs which require careful adjustment, and even returning spring 51 can be omitted. My feeler is stopped by the filling until that is reduced to the predetermined point when the dead weight of all the parts comes down on the shifter arm in a straight action which positively operates it. There are no parts which have any tendency to twist or bind, but if the calipers should bind on the bobbin, they will be kicked off by the action of the cam and spring 39, or if the spring should break or should be too weak, the hub and calipers, being pivoted to rock lengthwise of the lay beam, will be swept out of the way by the movement of the shuttle.

It is evident that instead of extending the knock-off arm to reach the shifting arm, the shifting arm could be lengthened or bent in order to reach the knock-off arm.

While I prefer to use two-legged calipers in connection with a bobbin which has no slot, thereby saving the expense of forming a slot in the bobbin, I may however, as shown in Fig. 12, use for a feeler a single

blade 150 in connection with a bobbin such as 151 with a slot 152 which is turned to the vertical position instead of the horizontal.

With such an arrangement, when the yarn 5 153 which, as shown, extends across the slot in such a manner as to keep the blade 150 out of slot 152, runs out to such a point that the blade is allowed to fall through as shown by the dotted lines, the shifter arm will be 10 operated in the same manner as when the caliper feeler is used.

In such a case, however, guard 23 should 15 be so adjusted that the blade cannot go too far into the bobbin, as it might possibly catch in the slot and prevent the shuttle 20 from sweeping it up out of the way as shown by the dotted lines, if the lifting springs should fail to act.

My invention covers a downwardly de- 20 pending feeler free to move vertically and adapted to rock lengthwise of the lay beam and means independent of the shuttle to permit it to drop and to lift it just before the shuttle is picked.

25 By the use of the term "filling changing mechanism" in this specification, I intend to cover broadly any mechanism which will act either to automatically replenish the filling by changing the shuttle or bobbin, replacing 30 either by a full one without finally stopping the loom, or mechanism which merely stops the loom so that the filling can be changed by hand.

I show such a construction in Figs. 13 35 and 14 which represent one end of the breast beam at one side of a plain or fancy loom. When used on a fancy loom, I prefer to place my devices at the side opposite from the boxes.

40 160 is the breast beam, 161 the shipper handle which, when the loom is running, rests in a notch 164 from slot 162 in guide 163, 172 is the slide, 170 the filling fork fingers, 171 the weft hammer, 175 the shipper knock-off lever, all of well known construction.

To the breast beam at 185 preferably over the knock-off lever, I pivot a member having an arm 187 adapted to engage the shipper 50 handle and to move it to stop the loom, as shown by the dotted lines, and an arm 186. To arm 186 I pivot a tip lever K one end of which 183 is the shifting arm and extends out under knock-off arm 73 while the 55 other end 182 which is the heavier rests normally on stop 184.

To weft hammer 171, I attach a finger 180 with a head 173 which extends out sidewise and normally moves back and forth with 60 the weft hammer over the end 182 of the tip lever. When the yarn has almost run out, my feeler drops, and arm 73 engages shifting arm 183 by bearing down on it. This lifts end 182, as shown by the dotted lines

in Fig. 13, in front of head 173 so that as 65 weft hammer 171 moves up to the breast beam, head 173 forces tip lever K with arms 186 and 187 to the position shown in the dotted lines in Fig. 14, thus moving shipper 161 to stop the loom.

70 My device does not interfere with the feeler fork mechanism for stopping the loom when the filling breaks, but also stops the loom just before the filling on a bobbin runs out, thereby making it unnecessary 75 for the weaver to turn back the chain to locate the pick.

I claim:

1. In a loom having a movable shifting arm adapted to operate filling replenishing 80 mechanism, and a lay beam having a shuttle box, the combination of a slide strip free to slide vertically on the lay beam, a feeler shaft so carried by the slide strip as to extend across and over the shuttle box, a collar adjustable thereon, a hub which has a fixed depending leg pivoted on such shaft, an adjustable leg carried by the hub, a screw which passes through a smooth hole in the first named leg and through a threaded hole 90 in the adjustable leg, a spring plate slotted at the bottom to receive the screw and pivoted on the shaft, a returning spring fixed at one end to the shaft and at the other end to the spring plate, a bracket slotted 95 at the top to engage the shaft and at the bottom to receive the screw, a feeler blade adjustably attached to the bracket, and a knock-off arm fixed to the feeler shaft and in operative relation with the shifting arm, 100 with means independent of the shuttle to permit the slide and feeler to drop and to lift them just before the shuttle is fixed.

2. In a loom having a movable shifting arm adapted to operate filling replenishing 105 mechanism, and a lay beam having a shuttle box, the combination of a slide strip free to slide vertically on the lay beam, a feeler shaft so carried by the slide strip as to extend across and over the shuttle box, a hub 110 pivotal on the feeler shaft, a caliper feeler which extends downward from the hub in a position to engage the filling at one end on a bobbin in a shuttle in the shuttle race, an auxiliary feeler blade carried by the 115 hub in a position to engage the filling on another part of the bobbin, spring means between the hub and feeler shaft for returning the hub to its normal position, and a knock-off arm forming part of the feeler 120 shaft and in operative relation with the shifting arm, with means independent of the shuttle to permit the slide and feeler to drop and to lift them just before the shuttle is picked.

125 3. In a loom having a movable shifting arm adapted to operate filling replenishing mechanism, and a lay beam having a shuttle

box, the combination of a slide strip free to slide vertically on the lay beam, a feeler shaft so carried by the slide strip as to extend across and over the shuttle box, a hub 5 pivotal on the feeler shaft, a caliper feeler which extends downward from the hub in a position to engage the filling on a bobbin in a shuttle in the shuttle box, spring means between the hub and feeler shaft for returning 10 the hub to its normal position, and a knock-off arm forming part of the feeler shaft and in operative relation with the shifting arm, with means independent of the shuttle to permit the slide and feeler to drop and to 15 lift them just before the shuttle is picked.

4. In a loom having a movable shifting arm adapted to operate filling replenishing mechanism, and a lay beam having a shuttle box, the combination of a slide strip 20 vertically slidable on the lay beam, a feeler shaft so carried by the slide strip as to extend across and over the shuttle box, a hub so pivoted on the feeler shaft as to rock lengthwise of the lay beam, a caliper feeler 25 carried by the hub in a position to engage the filling on a bobbin in a shuttle in the shuttle box, spring means between the hub and feeler shaft for returning the hub to its normal position, and a knock-off arm 30 integral with the feeler shaft in operative relation with the shifting arm, with a slide rod attached to the slide strip, stops carried thereby, a cam, means for revolving the cam, and a lever operative by the cam which extends 35 between the stops, together with a spring which normally keeps such lever in the raised position.

5. In a loom having a movable shifting arm adapted to operate filling replenishing 40 mechanism, and a lay beam having a shuttle box, the combination of a slide strip vertically slidable on the lay beam, a feeler shaft so carried by the slide strip as to extend across and over the shuttle race, a hub 45 pivotal on the feeler shaft, a feeler which extends downward from the hub in a position to engage the filling on a bobbin in a shuttle in the shuttle box, and a knock-off arm forming part of the feeler shaft and in 50 operative relation with the shifting arm, with means independent of the shuttle to permit the slide and feeler to drop and to lift them just before the shuttle is picked.

6. In a loom having a movable shifting 55 arm, a feeler shaft in operative relation therewith, and a depending feeler pivoted to rock thereon lengthwise of the lay beam, combined with means independent of the shuttle to permit the shaft and feeler to 60 drop and to lift them just before the shuttle is picked.

7. A feeler mechanism for looms comprising a feeler shaft which extends across and above a shuttle box, a collar adjustable

thereon, a hub which has a fixed depending leg and is pivoted on such shaft, an adjustable leg carried by the hub, a screw which passes through a smooth hole in the first named leg and through a threaded hole in the adjustable leg, a spring plate slotted at the bottom to receive the screw and pivoted on the shaft, and a returning spring fixed at one end to the shaft and at the other end to the spring plate, combined with a bracket slotted at the top to engage the shaft and at the bottom to receive the screw, and a feeler blade adjustably attached to the bracket. 65

8. A feeler mechanism for looms comprising a feeler shaft which extends across and above a shuttle box, a collar adjustable thereon, a hub which has a fixed depending leg and is pivoted on such shaft, an adjustable leg carried by the hub, a screw which passes through a smooth hole in the first 80 named leg and through a threaded hole in the adjustable leg, a spring plate slotted at the bottom to receive the screw and pivoted on the shaft, and a returning spring fixed at one end to the shaft and at the other end to the spring plate, combined with means independent of the shuttle to permit the feeler shaft to drop and to lift it just before the shuttle is picked. 85

9. A feeler mechanism for looms comprising a feeler shaft which extends across and above a shuttle box, a collar adjustable thereon, a hub which has a fixed depending leg and is pivoted on such shaft, an adjustable leg carried by the hub, a screw which passes 90 through a smooth hole in the first named leg and through a threaded hole in the adjustable leg, a spring plate slotted at the bottom to receive the screw and pivoted on the shaft, and a returning spring fixed at one end to the shaft and at the other end to the spring plate. 95

10. In a loom having filling changing mechanism operative by a movable shifting arm, a feeler shaft, a knock-off arm carried 100 thereby in operative relation with the shifting arm, and a feeler depending from the feeler shaft and pivoted to rock lengthwise of the lay beam, combined with means independent of the shuttle to permit the shaft and feeler to drop and to kick them up out of the way just before the shuttle is picked. 110

11. In a loom, filling changing mechanism operative by a movable shifting arm, a feeler shaft, a knock-off arm carried thereby in 120 operative relation with the shifting arm, and a feeler depending from the feeler shaft and pivoted to rock lengthwise of the lay beam adapted to feel for and to be held up by the filling on the bobbin in the working shuttle, spring means adapted to return the feeler to its normal position, combined with means independent of the shuttle to permit 125

the shaft and feeler to drop and to kick them up out of the way just before the shuttle is picked, whereby when the filling has almost run out, the filling changing mechanism will operate.

12. In a loom having a movable shifting arm, a feeler shaft in operative relation therewith, and a depending feeler pivoted to rock thereon lengthwise of the lay beam 10 away from the picker mechanism, combined with means independent of the shuttle to permit the shaft and feeler to drop and to knock them up out of the way just before the shuttle is picked.
- 15 13. In a loom having a movable shifting

arm, a feeler shaft in operative relation therewith, a knock-off arm forming part of the feeler shaft and in operative relation with the shifting arm, and a feeler depending from the feeler shaft and pivoted to rock lengthwise of the lay beam from a vertical position in the direction of the rebound of the shuttle, combined with means independent of the shuttle to permit the shaft, the knock-off arm and the feeler to drop 20 and to lift them just before the shuttle is picked.

In testimony whereof I have affixed my signature.

JOZEF GOTERCH.
